DELIVERY TABLE

Sidney J. Stone, Lyndhurst, Ohio

Application June 19, 1947, Serial No. 755,700

4 Claims. (Cl. 311—7)

1

This invention relates to improvements in a delivery table and more particularly to a table of the order of an auxiliary bed of very narrow width adapted to be placed alongside an ordinary hospital bed or at the end of a delivery table.

One of the objects of the present invention is to provide a narrow portable bed adapted to be wheeled alongside an ordinary hospital bed after which a woman in labor lying upon the hospital bed may be turned around, her hips placed upon the auxiliary table here disclosed, her legs properly positioned in leg holders and thereafter the attending obstetrician may deliver the baby thus converting any labor bed into a delivery table.

Another object of the present invention is to connect my improved delivery table with the hospital bed so that the delivery table will not move during a delivery operation.

Another object of the present invention is to provide adjustability as to the height of my improved delivery table so that the delivery table portion may be moved downward beneath a woman's hips momentarily to permit the placing of a sterilized sheet beneath her hips, after which the table is again moved up to hip-supporting position.

Another object of the invention is to provide adjustability and adaptability of the various parts so that various patients may be accommodated comfortably.

Other objects and advantages of the present invention will be apparent from the accompanying drawings and description, and the essential features thereof will be set forth in the appended claims.

Another object of the invention is to provide adjustment beyond the range of ordinary tables to secure more favorable positions desirable in complicated deliveries.

By using this table the thighs may easily be lowered to the so-called "Walcher" position—the advantage of which is well recognized by trained obstetricians.

In the drawings,

Fig. 1 is an end elevational view of one embodiment of my invention;

Fig. 2 is a top plan view of the same, with parts broken away to more clearly show the attachment of the delivery table to the hospital bed.

Fig. 3 is a fragmental side elevational view of the same device taken from the right-hand side of Fig. 1;

Fig. 4 is a fragmental sectional view taken

along the line 4—4 of Fig. 1, the same being somewhat enlarged;

Fig. 5 is an enlarged fragmental sectional view taken along the line 5—5 of Fig. 1;

Fig. 6 is an enlarged view of a portion of the left side of the frame as shown in Fig. 1, with parts broken away to more clearly show the construction; while

Fig. 7 is an enlarged fragmental view of the mid portion of the right-hand side of the frame as shown in Fig. 1 with parts broken away to more clearly show the construction.

It is well known that there are difficulties in many hospitals in providing sufficient delivery tables although there are usually sufficient labor beds. The present invention makes it possible to use every bed as a delivery table.

Another disadvantage in present day practice is the difficulty of moving an anesthetized patient from a labor bed on to a delivery table. By the use of my present invention, it is not necessary to move the patient from the labor bed itself but instead her body is manipulated on the labor bed so as to utilize my improved delivery table during the delivery operation. Thus, undesirable movement of the patient is obviated.

In the various views I have shown one embodiment of my invention wherein a light frame 10 is portably mounted upon casters 11 so that it may be wheeled about from place to place. The details of this frame are unimportant except as hereinafter specifically referred to. In the drawings four end posts 10a are shown, the two posts at one end being connected by an upper cross bar 10b and a lower cross bar 10c. Two longitudinally extending frame members 10d connect the two upper end frame members 10b. One longitudinally extending frame member 10e connects the two bottom end frame members 10c. These members are all connected together by suitable T-shape fittings as shown. It will be noted that this provides a strong frame but one which leaves the space clear for the attending physician to stand or sit close to the right-hand edge of the delivery table as shown in Fig. 1.

The delivery table portion of my device consists of a bed portion 12 mounted for vertical movement relative to the frame 10. Preferably, a quick acting device is provided for lowering and raising the table portion momentarily to slip a sheet under the woman's hips or for a similar purpose. The drawings show one means suitable for this purpose comprising a toggle 13 although my invention is not limited to this specific means. The bed 12 rests upon a structural base

14 to which is rigidly attached a downwardly extending stem 15 which slidably engages within the hollow portion of a pedestal 16 which in turn is rigidly secured to the two frame members 10d. Operating means for the toggle is of a simple type and comprises a shaft 17 which is connected to a yoke 18, each arm of which has a clevis connection 19 with the mid point of one of the toggles 13, there being one on each side of the pedestal 16. Rigidly secured to the frame member 10b is a bracket 20 on which is oscillatably mounted a handle 21 which is pivotally connected to the shaft 17 at the point 21a. When the bed 12 is in raised position as shown in Fig. 3 the toggles 13 are slightly over center toward the right and the pin 16a fixed in the pedestal limits further movement of the toggle toward the right. When it is desired to lower the bed the handle 21 is moved toward the left as viewed in Fig. 3 permitting the toggles 13 to break toward the left until the bottom of the stem 15 strikes the bottom 16b of the hollow of pedestal 16, or other suitable limiting means may be provided.

Means is provided for attaching the delivery table to a hospital bed so that the parts will not move during a delivery operation. Any means for attachment to a specific type of bed is within the scope of my invention. As clearly shown in Figs. 1, 2, 3, and 6 the means here provided contacts with one of the usual longitudinally extending frame members 22 of a common type of hospital bed. The bed mattress 23 is shown resting upon this frame. Each of the upright frame members 10a nearest the hospital bed is hollow and receives a bar 24 which is threaded to receive an adjusting nut 25. The upper end of the bar 24 is provided with a diametrically extending slot or recess 24a adapted to receive the downturned leg 22a of the angle member 22. With the two bar members 24 in lowered position the delivery table is wheeled up to the hospital bed with the slots 24a directly beneath the structural angle leg 22a. The nuts 25 are then manipulated to raise the rods 24 until the structural member 22a firmly engages in the notches 24a. This holds the delivery table in fixed position relative to the hospital bed. Nuts may be manipulated to cause rods 24 to lift the top of mattress 23 to a level with bed portion 12, if desired.

The vertical posts 10a farthest from the hospital bed are hollow and receive the adjustable posts 26, each of which is provided with a series of horizontal openings extending clear through the posts as indicated at 26a. The T member 27 is provided with aligned openings 27a through which passes a pin 28 which engages in one of the selected openings 26a so as to hold the post 26 at the desired height. As clearly seen in Figs. 2 and 3 there is one of these posts 26 at each side of the delivery table bed 12. At the top of each of these posts is a leg holder 29. Referring to Figs. 1 and 5, a block 30 is mounted to swivel about each post 26 by means of a thumb screw 31 which engages in an annular groove 32 in the top of the post 26. Mounted in each block 30 is an arm 33 having a shank passing through a suitable opening in the block 30 so that the shank of the arm 33 is adjustable in a direction at right angles to the post 26. The end of each arm 33 is provided with a flattened top surface 33a and a thumb screw 34 threaded into the block 30 bears against the surface 33a to hold the arm 33 in various adjusted positions. Each leg holder 29 has a downwardly extending ear 29a which is pivotally mounted on a bracket 35 by means of

the horizontally extending pin 36. Each bracket 35 is mounted to swivel about the vertically extending portion 33b of the associated arm 33, by means of a thumb screw 37 which engages in an annular groove 38 at the upper end of the arm portion 33b. This is clearly shown in Fig. 4. Preferably openings 26a are provided to permit adjustment of leg holders 29 to hold the knee below the abdomen, if desired.

10 Preferably, the unit is finished by attaching side plates 39 and end plates 40 extending downwardly from the bed base 14 so as to completely enclose the operating parts of the toggles 13. The end plates are slotted as shown at 40a so as to permit the bed 12 to be lowered with reference to the frame members 10d.

15 The operation of my device should now be clear. The delivery table is moved alongside of the bed and the parts 24 and 25 are manipulated to secure the delivery table against movement relative to the bed frame. The table bed portion 12 is adjusted to the proper height by properly adjusting the bottom pivot pin 13a of the toggles in a suitable opening 13b in the pedestal 16. A woman in labor lying upon bed 23 is moved sideways on the bed by simply sliding her body and without any danger of injuring the mother or the child. The woman's hips are then moved off the bed slightly so that they rest upon the narrow delivery table bed 12. I find that a width of the order of six to ten inches is sufficient for this bed because it is desirable that the bulk of the woman's weight should rest upon the hospital mattress 23. The length of the bed portion 12 may be anything desired but is usually of the order of several feet. During the preparation of the patient for delivery it is usually desirable to slip a sterilized sheet beneath her hips. The attending physician may do this easily by operating the toggles 13 to momentarily lower the table portion 12 at which time the patient's weight resting upon the bed 23 and the support of the legs in the leg holders 29 is sufficient to permit this operation. After this the bed 12 is then raised to the proper level by means of the toggles 13. It will be noted that the leg holders 29 may be freely tilted in any direction about the pivot connection 36 and the swivel connection 35, 37, 38. The leg holder, however, may not tilt sidewardly because of snug engagement of the ear 29a in the bifurcated upper end of the bracket 35. The legs of the patient are usually secured to the leg holder by means of straps passing through the slotted openings 29b.

55 Referring to Figs. 1 and 2, it will be noted that the space vertically beneath the edge 12a of the table 12 is clear. In other words, the frame members 10d and 10e are back beneath the bed portion 12 leaving the space clear for the attending physician to stand or sit as close as he desires to the delivery table and permitting the placing of a basin or other receptacle directly beneath the edge 12a of the table 12. After the baby has been delivered the patient is slid back upon the bed 23 with a minimum of movement, the bar members 24 are moved downwardly out of engagement with the bed frame members 22 after which the improved delivery table may be rolled away if desired.

60 70 What I claim is:

1. A delivery table comprising a frame portion adapted to be placed alongside a bed, a narrow bed portion supported on said frame portion, said bed portion having a length parallel to the side 75 of said bed of the order of a few feet, said bed

portion having a width normal to the side of said bed of the order of six to ten inches, means for adjusting the top of said bed portion to a normal position level with the top of the body supporting surface of said bed, and other quickly operable means for lowering the entire top of said bed portion below, and for returning the same to, said normal position.

2. A delivery table comprising a frame portion, wheels supporting said frame portion for movement along a surface, means on said frame portion for attachment to a bed, a narrow bed portion supported on said frame portion, said bed portion having a length parallel to the side of said bed of the order of a few feet, said bed portion having a width normal to the side of said bed of the order of six to ten inches, means for adjusting the top of said bed portion to a normal position level with the top of the body supporting surface of said bed, and other quickly operable means for lowering the entire top of said bed portion below, and for returning the same to, said normal position.

3. A hospital table of the class described comprising a frame, a table top, means supporting said table top on said frame for movement up and down relative thereto, said support means including adjustable means for supporting said table top in a normal position at a predetermined height, and said support means including quickly operable means for lowering said entire table top

below, and for returning said table top to, said normal position.

4. A hospital table of the class described comprising a frame, a table top, means supporting said table top on said frame for movement up and down relative thereto, said support means including adjustable means for supporting said table top in a normal position at a predetermined height, and said support means including toggle means for lowering said entire table top below, and for returning said table top to, said normal position.
